UNITED STATES PATENT OFFICE.

THOMAS WATTS, OF PERSHORE, COUNTY OF WORCESTER, ENGLAND.

THILL-COUPING.

SPECIFICATION forming part of Letters Patent No. 448,284, dated March 17, 1891.

Application filed May 17, 1890. Serial No. 352,147. (No model.) Patented in England April 12, 1889, No. 6,265.

To all whom it may concern:

Be it known that I, THOMAS WATTS, carriage-builder, a subject of the Queen of Great Britain, residing at High Street, Pershore, in the county of Worcester, England, have invented certain new and useful Improvements in Shaft-Connections for Wheeled Vehicles, for which Letters Patent have been granted to me in Great Britain dated April 12, 1889, and numbered 6,265; and I do hereby declare the following to be a full, clear, and exact description of the invention, reference being had to the accompanying drawings, which form part of this specification.

15 This invention relates to noiseless connections for the shafts of two-wheeled vehicles.

Figure 1 of the accompanying drawings represents, in side elevation, a two-wheeled vehicle provided with noiseless shaft-connections constructed and arranged according to my said invention. Fig. 2 represents a transverse vertical section of the rear connection upon an enlarged scale to that of Fig. 1, while Fig. 3 also represents a transverse vertical section of the front noiseless connection. Fig. 4 is a top side plan of Fig. 2, while Fig. 5 is a top side plan of Fig. 3. Fig. 6 represents a longitudinal vertical section of the said connection upon the dotted lines A B, Fig. 3; and Fig. 7 represents a transverse vertical section upon the dotted lines C D, Fig. 5. The only difference between the said sections Figs. 6 and 7 is that the cushion-fulcrum or rubber block which is interposed between the 35 inside of the metallic attachment parts and the under side of the shaft is shown distended and without the shaft pressing upon it. Fig. 8 represents a front elevation of the said connection, and Fig. 9 a side view of it. Fig. 10 represents a section of the cushion fulcrum-box, and Fig. 11 the connection-plate of it.

a is an open-topped fulcrum-box or hollow casting, provided with gapped sides a² and necks a³, one of which latter is directed inwardly from the inner walls of the said hollow casting, while the other is directed outwardly from the outer walls or sides. Directed vertically through the bottom of the said casting is a hole a⁴, wherethrough a connecting screw-pin b passes and fits, and by means of which the attachment-arm c is con-

nected by the passing of the screw-nut b² upon the wormed end of the said hanging screw.

d is a fulcrum or shaft-attachment plate, and e is the shaft to which the said plate is attachedly connected by bolts or strap-clips f passing through or around the said shafts, and with their wormed ends fitted with screw-nuts for making the necessary attachment. This said plate d has hanging eyes or bracket- 60 bearings d², which take upon the necks a³ of the box-casting a, as aforesaid.

Fitted within the hollow of the fulcrum-box or casting and extending or protruding through the open middle d³ of the attachment 65 plate d is a rubber or other yielding block g, constituting a cushion-fulcrum, which, when in position, as in Figs. 1, 2, 3, and 6, interposes between the under sides of the shafts and the bottom and insides of the casting a. 70

Directed transversely through the hollow necks a³ of the box-casting a and the eyes d² of the shaft-plate d, and also the middle of the rubber block, is a pin h, with a head h² at one end and a screw-nut h³ at the other 75 end, whereby the whole of the parts of the attachment are connected together.

The parts of the connections are put together as follows: First pass the hanging screw-pin b in position and thread the shank 80 of it through the attachment-arm, then screw home the screw-nut b² upon the screwed end of the said pin. Then pass the bracket-eyes d² into the hollow of the box-casting a, and by a lateral sliding motion from right to left 85 of the said shaft-plate d, the bracket-eyes d² are passed onto the necks a³, as represented in the views Figs. 6, 7, and 9. This done, insert the rubber block g through the middle opening d³ of the shaft-attachment plate d 90 into the hollow of the casting a and with the said block g resting at the bottom of the said casting and with its upper end protruding or standing above the top side of the plate d. The said shaft-attachment parts, as aforesaid, 95 are secured or connected together and the cushion-fulcrum retained in its place by the passing through the said parts of the pin h, which is then secured by the nut h³.

In affixing the noiseless connection, place 100 the under side of the shaft upon the top of the rubber block and pass the ends f² of the

screw pins or bolts f through the holes or eyes d^4 , made through d^5 of the attachment-plate d , when on the screwing home of the nuts f^3 the connection is made. It will thus be seen that the upper part of the rubber block extends above the top side of the shaft-attachment plate and takes its bearing upon the under side of the shaft in such a manner that the rubber block, on pressure being applied, is forced into the hollow of the casting and plate and through the interstices or gaps i between them, thereby keeping asunder the said metallic parts and preventing the joints from clattering. It will be also observed that the shaft-attachment plate d or the bearings d^2 of it turn upon the bearing-necks a^3 of the other part.

Having thus described my invention, I claim as new and desire to secure by Letters Patent—

1. The combination of the hollowing casting a , having the hollow necks a^3 a^3 , with the shaft-plate d , provided with the bracket-eyes d^2 , the rubber block g , inserted in the hollow of said casting a , and the bolt L , passing through said hollow necks and said rubber blocks, substantially as described.

2. In a shaft attachment, the combination, with a plate adapted to be secured to a shaft having a hole in the top and provided with bracket-eyes, of a hollow casting pivotally attached to said bracket by a horizontal bolt, and a rubber block fitted in the hollow casting and projecting through the hole in the plate, substantially as shown and described. 35

3. In shaft attachments, the combination, with the shaft e and the attachment-arm c , of the hollow casting a , secured to said attachment-arm by the vertical bolt b and nut b^2 , the shaft-attachment plate d , secured to the shaft and formed with an opening d^3 in its middle part and pivotally attached to said hollow casting, the rubber block g , and the bolt l , passing through the said block g and pivotally connecting the casting a and plate 40 d , substantially as shown and described. 45

In testimony that I claim the foregoing I have hereunto set my hand this 29th day of March, 1890.

THOMAS WATTS.
